UNITED STATES PATENT OFFICE.

GEORGE W. WAY, OF PORTLAND, MAINE.

DRESS-SKIRT ELEVATOR.

SPECIFICATION forming part of Letters Patent No. 416,022, dated November 26, 1889.

Application filed August 6, 1889. Serial No. 319,867. (No model.)

To all whom it may concern:

Be it known that I, GEORGE W. WAY, a citizen of the United States, residing at Portland, in the county of Cumberland and State 5 of Maine, have invented certain new and useful Improvements in Adjustable Supports for Dress-Skirts; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 My invention relates to a device for raising the lower edge of the skirts on ladies' dresses.

It is well known that a dress which is made of proper length for wear in the house is 20 often too long when walking on the street, and this is particularly true in wet and rainy weather. Many expensive dresses are spoiled by allowing their lower edges to drag ever so slightly on the ground or pavement. So 25 far as I am aware, no convenient and effective device has been used for evenly raising the lower edge of the skirt to a greater or less height.

The object of my invention is to raise and 30 lower the bottom of the dress-skirt at will and at the same time preserve the proper hang of the drapery. This I accomplish by means of my invention, which consists of the device as set forth in the claims.

35 I illustrate in the accompanying drawings a specific form of my device.

In the drawings, Figure 1 is a side view of a dress-skirt, showing my device in position. Fig. 2 is a central vertical section through 40 the catch, and Fig. 3 is a perspective view of the same without the cord.

A represents the waistband of the skirt, and B is the skirt proper. Attached to the upper part of the skirt, preferably to the 45 waistband, is the catch or fastening C. This catch consists of a tube having bell-shaped ends. On the upper end is formed a lug c, containing holes by which it is sewed or otherwise attached to the dress. There is also 50 formed in the upper end a notch c'. A cord D passes through the tube, and has secured

to it at numerous places small annular flanges d, which are adapted to catch in the notch c', and so prevent the cord from being drawn downward through the tube. The tube C is 55 attached to the lower portion of the waistband and the greater part of it is located beneath the fabric of the skirt, so that the cord passes from the inside to the outside of the dress through the tube. The notch c' is 60 placed preferably toward the front. The lower end of the cord is formed into several branches d' d' d'. These branches are here shown as pieces of tape, the upper ends of which are secured to the lower end of the 65 cord D, their lower ends being secured to the skirt preferably on the inside, and at a point about half-way between the top and bottom of the skirt.

It is designed to use one of my suspending-cords on each side of the dress, each cord having several tapes or branches on its lower end. The lower ends of these tapes are attached to the dress about equally distant from each other around the skirt and about 75 half-way down. The cord has a loose fit within the tube and slides freely through it when not caught in the notch c'.

The use of the device is obvious from its construction. When it is desired to lift the 80 lower edge of the skirt, the cord is drawn upward through the tube and one of the flanges d allowed to catch in the notch c'. These flanges are numerous enough so that the skirt can be raised much or little, as required. It can be lowered into place by simply releasing the cord from the catch, the cord having a free longitudinal movement when so released and moving freely up and down. The end of the cord D which hangs 90 down outside of the skirt may be provided with a suitable ornament. The tube C, being provided, as it is, with walls which are interposed between the rod and the dress fabric, protects the fabric from the wear incident to drawing the cord up and down. 95

It will be seen that the device can be quickly and easily operated and will result in great saving to the dress. When drawn up, the entire lower edge of the dress is raised equally 100 and the hang of the skirt is not materially disturbed. In fact, the drapery thus pro-

duced is rather ornamental than otherwise, and it is for this reason that the attachment of the cord at the center of the skirt becomes important. If the cords were attached at or 5 near the bottom, the proper drapery could not be obtained, and if near the top the skirt could not be easily lifted. When not in use, the cord is allowed to hang over the back edge of the tube, so that it slides freely without catching in the notch *c'*.

It is obvious that many modifications can be made in the device here illustrated and particularly described without departing from my invention as embodied in the claims.

15 I claim—

1. The herein-described support for dress-skirts, consisting of a tube secured vertically to the upper part of the dress-skirt and having in its upper end a notch or recess, and a cord

attached to said skirt and passing through 20 said tube, and having enlargements whereby it may be retained in said notch, substantially as described.

2. The herein-described support for dress-skirts, consisting of a tube secured vertically 25 to the upper part of the dress and having a notch or recess in its upper end, and a cord secured to said skirt and passing through said tube, and having annular flanges secured to it at intervals, whereby it is retained in said 30 notch, substantially as shown.

In testimony whereof I affix my signature in presence of two witnesses.

GEORGE W. WAY.
